UNITED STATES PATENT OFFICE.

FRANK W. ANDREWS, OF WAPAKONETA, OHIO, ASSIGNOR, BY MESNE ASSIGNMENTS,
TO SUPERIOR REFRIGERATION, INC., OF WAPAKONETA, OHIO.

GAS-LIQUEFYING APPARATUS.

Original application filed May 14, 1917, Serial No. 168,525. Divided and this application filed May 23,
1922. Serial No. 563,097.

To all whom it may concern:

Be it known that I, FRANK W. ANDREWS, a citizen of the United States, residing at Wapakoneta, in the county of Auglaize and 5 State of Ohio, have invented certain new and useful Improvements in Gas-Liquefying Apparatus, of which the following is a specification.

My invention relates to refrigerating apparatus and more particularly to a compressor, and condenser for subjecting gaseous refrigerant medium to pressure and condensation whereby it is reduced to a liquid form.

The object of the invention is to simplify the structure as well as the means and mode of operation of apparatus for reducing gaseous bodies to liquid form, whereby it will not only be cheapened in construction, but will be more efficient in use, economical in 20 operation, of compact form, and unlikely to get out of repair.

A further object of the invention is to provide a unitary structure of comparatively small size embodying as a single unit, the 25 compression cylinder, the actuator, and a supporting base containing condenser and storage compartments.

A further object of the invention is to provide an improved form of compressor, for 30 refrigerating medium or other gaseous bodies, and to afford therein improved intake and discharge ports and control means therefor, by which the efficiency of such compressor will be materially increased.

With the above primary and other incidental objects in view as will more fully appear in the specification, the invention consists of the features of construction, the parts and combinations thereof, and the mode of 40 operation or their equivalents as hereinafter described and set forth in the claims.

Referring to the accompanying drawings, Fig. 1 is a vertical sectional view of the condensing unit forming the subject matter 45 hereof, illustrating the relative relation and interconnections of the compressor, the condenser and receiver. Fig. 2 is a detail sectional view of the cross head and driving connection for the pump or compressor portion of the structure. Fig. 3 is a transverse sectional view, through the annular gas inlet chamber of the compressor. Fig. 4 is a detail cross sectional view of the compressor cross head. Fig. 5 is a sectional plan view of the 50 cylinder 20. Fig. 6 is a side elevation thereof viewed from the inlet and outlet side, showing in dotted lines, the relative positions of the condenser coils and spray pipe. Like parts are indicated by similar characters of reference throughout the several 60 views.

The compressor construction illustrated in detail in Fig. 1 comprises a vertically disposed cylinder 20, mounted upon an enclosed hermetically sealed crank housing 21. The 65 driving crank 22 is mounted within the closed housing 21 in inward projecting sleeves or bearing boxes 23, which are closed at the outer ends as at 24. There is mounted within the closed housing 21 upon the crank 70 shaft 22, a driving gear 25, which in the present instance has been shown as of internal spur gear type. The purpose of employing an internal gear is to reduce the structure to as compact a unit as possible by enabling a 75 driving pinion 26 to be located within the periphery of the drive gear 25. The drive pinion 26 is carried upon the armature shaft 27 of the electric motor 16. In the drawing 80 the gear has been shown provided with an extended hub 28. It is obvious that the gear 26 might be mounted directly upon an extension of the armature shaft 27. The shaft 27 and hub 28 extends through a packing gland 29. This packing gland is of considerable extent and serves to prevent gas or refrigerant leakage from the housing 21. It is to be noted that the opening for the driving connection of the gear pinion 26 is the 85 only exterior opening of the housing 21, and this opening is hermetically sealed by the packing gland 29. There is mounted within the cylinder 20 a reciprocating piston 30 connected by a piston rod or stem 31 with the yoke 32 of a Scotch cross head mounted 90 to reciprocate upon guides or ways 33 formed in the interior of the housing. The Scotch cross head is provided with the usual wrist pin bearing 34 sliding on the transverse ways or guides of the yoke. The construction is 95 such that the piston 30 is reciprocated by the rotation of the crank shaft in a straight path without any lateral binding tendency. Adjacent at its upper end the cylinder 20 is surrounded by a water chamber or jacket 100 35. This chamber communicates with a like chamber 36 in the head 37 of the cylinder. The chamber 36 is provided with a waste

outlet conduit 38 while the chamber 35 is provided with an inlet conduit 39 for cooling water. This water is conducted to the chambers 35 and 36 through the conduit 39 from the condenser chamber 7 hereinafter referred to. Formed in the interior of the head 37 is an integral sleeve 40. Mounted to reciprocate within the sleeve 40 is a head 41 for the piston chamber of the cylinder 20. This head 41 which comprises the outlet valve is of greater diameter than the bore of the cylinder 20 and is adapted to seat upon a seat ring 42 of rubber, fiber, composition or other material which will provide a tight seating contact. Such seating ring not only conforms itself to the valve head, but also cushions the impingement of the valve head thereby minimizing the noise of contact. This is highly desirable in residence units. In order that the valve 41 may be accurately seated it is provided with an integral bearing sleeve 43 of comparatively large diameter which is slidingly mounted within the sleeve 40 of the head 37. A retracting spring 44 located within the concentric sleeve 40 and 43 tends to seat the valve 41 upon the annular valve seat 42. The upper face of the valve 41 is provided with a concentric groove 45 in which is located a collar 46 of rubber, fiber, composition or other packing material which contacts with the lower end of the pendant sleeve 40 of the head at the upward limit of movement of the valve head 41, thereby cushioning the impingement of the valve head 41 upon the bearing sleeve 40. The interengaging valve sleeves 40 and 43 are of comparatively large diameter almost as large as the bore of the cylinder itself as can be seen by referring to Fig. 2. The valve head 41 which also forms the head for the cylinder 20 is guided accurately to and from its seat upon the packing ring or seat ring 42 by said sleeves. It is to be noted that the compressor has no inlet valve.

Immediately below the water jacket or cooling chamber 35 there is provided in the wall of the cylinder an annular concentric chamber 47 with which communicates a gas inlet conduit 48. The gas inlet chamber 47 is provided with a plurality of radially disposed ports substantially equally spaced throughout the periphery of the cylinder through which the gas passes from the annular inlet chamber to the interior of said cylinder. It is to be noted that the head 30 of the piston is of such length that when the piston is at the upper end of its stroke it extends beyond the inlet ports 49 of the gas inlet chamber, thereby effectively closing said ports. A gas outlet conduit 50 leads from the interior chamber of the head 37 above the plane of the valve head 41.

As the piston moves downward the valve head 41 is of course seated upon its seat ring

42 under the influence of its retraction spring 44. As the piston continues its downward movement it draws a partial vacuum in the upper portion of its cylinder to such extent that when it reaches the level of the gas inlet port 49, and uncovers said port the gas will rush in to fill such vacuum with great velocity and the result is equivalent to supplying gas to the compressor under an initial pressure. It has been found that the vacuum so drawn is equivalent to forcing the gas into the compressor cylinder under approximately twenty pounds pressure. By this means a greater volume of gas is handled at each operation, and the efficiency and capacity of the compressor is very materially increased. While the piston head 30 is provided with the usual piston or packing rings 51 more or less refrigerant or gass will leak past said rings to the cylinder beneath the piston head and extend to the crank housing 21. While the piston is accurately fitted to the bore of the cylinder and compression is maintained by the packing or piston rings 51 such leakage of the gas or refrigerant as may occur does no particular harm inasmuch as it cannot escape from the crank housing 21 which as before mentioned is hermetically sealed.

It will be understood that the crank housing 21 is partially filled with oil in order that the Scotch cross head by which the piston is driven may be effectively lubricated. In order to prevent the splashing of oil into the cylinder in excessive amounts, and to prevent the entrainment of oil in gas or refrigerant which may pass to and fro past the piston head during operation, and so be carried into the refrigerant discharge line, there is provided a wiping gland 52 located at the lower end of the cylinder, and surrounding the piston stem 31. This wiping gland comprises a collar 53 of felt or other yielding material, held in position by a perforate plate or collar 54. There is no attempt made to render the wiping gland 52 gas or refrigerant tight. The fact that gas or refrigerant may leak past the piston head into the crank housing 21 and the lower portion of the cylinder 20, tends to equalize to some extent the pressure on opposite sides of the piston head, and facilitates the ease of operation.

The gas outlet conduit 50 leads from the compressor head 37 to the condenser chamber 7 which is formed in the base 55 upon which the compressor 6 and its driving motor 16 are supported. The base 55 is divided into two chambers or compartments, the condenser chamber 7 and the receiving chamber 8. The condenser chamber 7 is situated at a higher level than the receiving chamber 8, as clearly indicated in Fig. 2. The refrigerant which is then in liquid form readily drains by gravity from the condenser cham-

ber 7 to the receiving chamber 8. Located within the condenser chamber 7 is a succession of coils in the condenser pipe or tube 56 with the initial end of which the gas conduit 58 communicates. The outlet of the condenser coil communicates with the reverse end of the conduit 58 with the cap 59 secured to the base 55. The conduit 58 through said cap or head 59 forms an intercommunicating conduit between the condenser chamber 7 and the receiver.

Located within the condenser chamber 7 below the plane of the condensing coil 56 is a water supply head comprising a transversely arranged water conduit 61 from which extends a plurality of perforated pipes or tubes 62. The pipes 62 are preferably arch-shaped as shown by dotted lines in the top plan view Fig. 5 and are provided at their upper sides with a series of small perforations 63 through which numerous jets of water are discharged upward. It will be understood that the condenser chamber 7 is normally completely filled with water in which the condenser coils 56 are submerged. The purpose of the spray or jet head for the cooling water is to distribute the water equally throughout the chamber 7 to secure more thorough and uniform circulation and to further insure all parts of the condensation coil 56 being reached by the cold water circulated through the chamber 7. This cooling water is conducted to the spray head or distributor in the bottom of the condenser chamber 7 through a water supply conduit 60 leading from any suitable source, such as a city water main, a tank, pump or other supply means. The supply of cold water is circulated through the condenser chamber 7 around the condenser coils 56 thence from the chamber 7 through a conduit 39 before mentioned, which leads from the chamber 7 to the annular or water jacket 35 of the cylinder 20. The water having passed through the chamber 35 about the cylinder and through the chamber 36 in the head 37, is discharged through the water outlet conduit 38, either as waste water or is conducted back to the tank, well, or other source of supply.

By the circulation of cold water about the condenser coil 56 within the chamber 7, the gaseous refrigerant previously compressed by the action of the piston 30 which leaves the compressor 6 in a heated condition, is cooled and condensed to a liquid form which flows from the coil 56 through the outlet or U-shaped bend 58, and is discharged into the receiver 8. As indicated in Fig. 2 the condenser coils 56 are located at slight inclination whereby the refrigerant will drain through said coils to the receiver 8 by gravity.

The receiver 8 is provided at one end with a head 64 screw threaded and suitably packed,

which may be removed for examination or cleansing of the interior of the receiving chamber. The movable head 64 may if so desired be provided with a transparent section 65 through which the contents of the receiving chamber may be examined to determine the quantity and condition thereof. The present application is a division of application Serial No. 168,525, filed May 14, 1917, now matured into Patent No. 1,419,097, dated June 6, 1922.

Having thus described my invention, I claim:

1. In a unitary gas liquefying apparatus, the combination of a hollow base, divided into a condensing chamber and a receiving chamber located at different levels with the condensing chamber at a higher level than the receiving chamber, a compressor pump mounted upon the base and discharging into the condensing chamber; a motor also on said base operatively connected with the compressor pump, a water jacket surrounding the compressor cylinder, and a conduit leading to the water jacket from the condenser chamber in said hollow base whereby the cooling water is circulated in a direction opposite the direction of circulation of the compressed gas.

2. A unitary gas liquefying apparatus, the combination of a hollow base divided into two integral compartments comprising a condensing chamber and a receiving chamber, a compressor pump mounted upon said base, an outlet conduit leading from the compressor pump through the condensing chamber of the base and discharging into the receiving chamber of said hollow base, a water jacket surrounding the cylinder of said compressor, a water supply conduit discharging into the condensing chamber of said hollow base and a conduit leading from said condensing chamber to said water jacket whereby cooling water may be circulated through said condensing chamber and thence through the water jacket of the compressor pump mounted upon said condensing chamber.

3. A unitary gas liquefying apparatus, the combination of a compressor pump, a condensing chamber and a receiver, of an outlet conduit from the compressor extending through the condensing chamber and discharging into the receiver, a spray pipe submerged in the cooling medium within the condensing chamber and supplying cooling medium thereto under pressure whereby the body of medium within the condensing chamber is maintained in a state of agitation about the gas conduit leading therethrough to the receiver, a cooling jacket surrounding the compressor cylinder and a conduit leading from the condenser chamber to the cooling jacket through which the cooling medium is discharged from said condenser chamber.

4. In a construction of the character described, the combination with a motor driven compressor, of a unitary hollow supporting base divided into two integral compartments located on different levels, one of which serves as a condensing chamber, and the other of which serves as a receiving chamber for the condensed gas passed thru the condensing chamber, a conduit for the com-

pressed gases leading from the compressor 10 thru the condensing chamber, and discharging into the receiving chamber, and inlet and outlet conduits for cooling medium communicating with the condensing chamber.

In testimony whereof, I have hereunto set my hand this 15th day of May A. D. 1922.

FRANK W. ANDREWS.
